UNITED STATES PATENT OFFICE.

CHARLES LEGLER, OF WILLARD, TEXAS.

DESIGN FOR A SHOVEL CLEANER OR KNIFE.

SPECIFICATION forming part of Design No. 17,295, dated May 3, 1887.

Application filed March 25, 1887. Serial No. 232,451. Term of patent 3½ years.

To all whom it may concern:

Be it known that I, CHARLES LEGLER, of Willard, (Trinity Post-Office,) in the county of Trinity and State of Texas, have invented a new and Improved Design for a Shovel Cleaner or Knife, of which the following is a full, clear, and exact description.

The drawing represents a side view of my newly-designed shovel cleaner or knife.

10 The novel feature of my design consists in a peculiar configuration of the blade and handle of the implement, substantially as hereinafter described, and shown in the drawing.

A is the blade, and B the handle. The blade 15 A is of flat configuration, having its edge *s* straight and with its opposite side margins straight for a portion of their length, as at *a a*, terminating where they project from the handle in ogee outlines *b b*. The handle B, which 20 is also flat, is of a straight outline configuration at its forward end, as at *c*, with its side margins partly of concavo-convex shape, as at *d d e e*, and joining on the one side a straight marginal continuation, *f*, terminating in a 25 straight back outline, *g*, having opposite

rounded ends *e' e'*. The opposite side margin of the handle from its junction with the convex outlines *e e'* on said side is also of straight configuration, as at *f'*, with a hollow or concave, *h*, in said straight portion *f'*. The handle is further ornamented by a bevel, *g*, on the several outline margins of its side. 30

Having thus fully described my invention, I claim as new and desire to secure by Letters Patent—

35 The design for a shovel cleaner or knife herein shown and described, the same consisting of a flat blade, A, and flat handle B, the blade being of a straight contour on its front and sides, with the latter terminating in ogee 40 outlines *b b*, and the handle being of a straight outline configuration at its forward and back ends and sides, joined by concavo convex outlines *d d*, *e e*, and *e' e'*, and with a concave, *h*, in one of its sides.

CHARLES LEGLER.
